(57) CLAIM

The ornamental design for a lighted fish net, as shown and described.

DESCRIPTION

FIG. 1 is a front view of a lighted fish net showing my new design;

FIG. 2 is a rear view of the lighted fish net;

FIG. 3 is a left side view of the lighted fish net, a right side view being a mirror image thereof;

FIG. 4 is a top view of the lighted fish net;

FIG. 5 is a bottom view of the lighted fish net;

FIG. 6 is a bottom front side perspective view of the lighted fish net; and,

FIG. 7 is a top front side perspective view of the lighted fish net.

The broken lines depict a fishing net and are included for the purpose of illustrating only and forms no part of the claimed design.
